UNITED STATES PATENT OFFICE.

FRANK P. DAUGHADAY, OF NORTON, MASSACHUSETTS.

BELT BUCKLE.

Application filed April 24, 1926. Serial No. 104,338.

This invention relates to belt buckles and is intended to provide a construction for an ornamental front which will permit the use of an ornamental front or escutcheon plate 5 of thin precious metal mechanically attached to a buckle body of stronger and more durable material in a simple, inexpensive and reliable manner, and further to permit the use of a panel of ornamental 10 material, such as pearl, onyx, celluloid or the like, which is positioned and held in place by means of the escutcheon plate itself.

Heretofore when using ornamental panels of pearl or other like material it has been 15 the practice to attach such panel by filling a counter-sunk orifice, bored in the back face of the panel, with soft metal and soldering that to the metallic buckle body. If it were desired to further ornament the panel 20 by superimposing ornamental strips or stripes of precious metal the front face of the pearl was grooved or channeled slightly, the grooves terminating in notches in the edges of the panel, and narrow strips of 25 gold or silver were inserted in such channel, their end portions being bent into said notches and folded back against the rear face of the panel so as to lock them in place. This method is not only very expensive, but 30 it permits the use only of straight line strips or bands since the channels themselves are cut by means of a small grinder.

The present invention overcomes these objections by providing an escutcheon plate 35 which may enter into the ornamentation of the buckle body to any desired extent to present any desired pattern, and at the same time serves as a simple and effective means for anchoring or securing a panel of ornamental material to the buckle body, while exposing any desired portions of the panel 40 in any desired pattern to view.

In general the invention comprises a buckle body or plate combined with an escutcheon plate, the front of the buckle body being depressed between its side edges to leave shallow lateral ledges between which the escutcheon plate is inserted, the escutcheon plate having its opposite end edges 45 inturned and folded around the corresponding end edges of the body to interlock these two parts together in a convenient and expeditious manner, the escutcheon plate being held against lateral displacement by lateral shoulders or ledges of the buckle body. This construction permits the use of orna-

mental sheets or panels of any desired material of any desired thickness which may be held firmly interposed between the outer escutcheon plate and the underneath buckle 60 body, as will be hereinafter explained.

In the accompanying drawings I have illustrated some buckle constructions embodying the principles of this invention, in which:

Figure 1 is a plan view of a buckle body exposing an inset pearl panel with a curvilinear over-stripe or band.

Figure 2 is a plan view of the buckle body construction formed to receive the pearl 70 panel.

Figure 3 is a central cross section of the buckle construction of Figure 1.

Figure 4 is a side elevation of the same with the belt-attaching clamping lever applied thereto.

Figure 5 is a cross section at right angles to the section of Figure 3.

Figure 6 is a transverse section showing a modified construction for receiving the 80 panel.

Figure 7 is a front view showing the cut-out pattern in the escutcheon plate with an underneath sheet of celluloid or the like.

Figure 8 is a longitudinal section of the 85 form of buckle shown in Figure 7.

The type of buckle to which the invention is shown applied in the accompanying drawings is what is known as the lever type of buckle whose body member embraces a front portion or member 1, and side flanges 2 which are sometimes further bent inwardly, as shown at 2^a, to make a guard for the belt passing through. The side flanges are pierced with openings to carry bearing pins or pintles 3 on which is mounted the clamping bail lever 4, through which the anchored end of the belt or strap is looped, while the free or tongue end of the belt is pinched against the front by the clamping arm of the lever, according to well known practice.

Such buckles readily lend themselves to various styles or ornamentation and there is a decided advantage in having the body of the buckle made of durable alloys strong enough to resist the strains and wear to which the body is subjected, while providing such body with an ornamental front of precious metal securely attached to the buckle body in a slight and convenient manner so that, at a minimum expense for material and labor, a strong and durable buckle,

having the finished appearance of a gold or silver buckle, may be produced.

In the present instance the greater portion of the front member of the buckle body 5 is depressed slightly below the side edge portions to leave slightly projecting shoulders or ledges 1^a, these side portions also being projected slightly beyond the two end edges of the front, as shown at 1^b, to form 10 additional shoulders. The central area of the front, when intended for the reception of a relatively thick panel of pearl or the like, is further depressed, as shown at 1^c, to form a shallow matrix for the reception 15 of a pearl front or panel 5, which is dimensioned to fit inside this recess when laid therein.

The pearl panel is held in place by means of an escutcheon plate 4 which may be of 20 any desired pattern or ornamental appearance, preferably made of thin precious metal, and dimensioned so that it will lie between the two side ledges 1^a and, by its engagement therewith, be prevented from 25 lateral or transverse movement. The opposite end edge portions of the escutcheon plate 4 are formed into end flanges 4^a which are bent around the opposite end edges of the front member of the body and crimped 30 inwardly behind the body, as shown in Figure 5. This thin metal can be very easily crimped in this fashion to form an interlocking connection or engagement with the end edges of the front member, the escutcheon 35 plate being held against lateral displacement by the shoulders 1^a and 1^b which, for appearance sake, lie substantially flush with the outer face of the escutcheon plate and serve also to protect its edges 40 against catching upon or engaging external objects. If it is desired to give a banded appearance to the pearl inlaid panel the escutcheon plate 4 may be stamped out to leave any desired arrangement or form of 45 bands, one of which is illustrated at 4^b as an arcuate or curved band integral with the escutcheon plate, and requiring no cutting or grinding of the pearl panel itself to produce the desired effect.

50 Instead of forming a panel-receiving recess in the front member of the buckle body, as above described, the whole interior portion of the front member 1, of the buckle body, between the two side ledges 1^a, may be flat or level, that is, the depression 1^c 55 may be omitted and a modified form of escutcheon plate 6, having an interior raised flange 6^a, overlapping the edges of the panel, may be used, as shown in Figure 6. In short, the recess or bed for the panel may be formed either in the outer escutcheon plate or in the body front which forms the back, behind the panel. In case an ornamental plate of thin sheet material 7, like celluloid, 60 is used the flat or unrecessed front member

1, as shown in Figure 7, will afford a level backing for such sheet material and the escutcheon plate 4, with its inturned or interlocking flanges 4^a, will cover and confine the interposed thin sheet of material, the 70 plate itself, as before stated, being cut out in any desired pattern to expose the celluloid backing. Mechanically the construction of buckle body and escutcheon plate will be the same, whether a celluloid backing be interposed or not. For ornamental purposes, however, where no backing or panel is used, the ornamentation may be embossed directly 75 on the escutcheon plate instead of punching out portions of the plate to expose an interposed backing element or member.

In practice the escutcheon plate is formed with its attaching or interlocking flanges projecting at nearly right angles to the body of the plate. The panel or sheet of ornamental material is placed upon the front member of the body, the escutcheon plate is placed over it with its end flanges engaging the opposite end edges of the body front of the buckle and the edge portions of the 90 flanges are then rolled or pressed down against the back face of the body forming, as shown in Figures 5 and 8, a complete and effective interlocking attachment presenting, at the same time, a finished edge to the end 95 edges of the buckle.

With this construction it is possible to bend up one of the inturned locking flanges 4^a, remove the escutcheon plate and either replace it with another plate of different design or substitute a panel of different appearance for the ornamental background. By this construction also the trouble and expense of cutting grooves in the face of the pearl inlay and of counter-boring the back 105 to permit it to be soldered to the buckle body is avoided.

What I claim is:

1. In a belt buckle, the combination with a body element comprising front and side 110 members, the front being depressed to leave raised lateral edges, a panel of ornamental material laid upon the front, an escutcheon plate whose side edges are dimensioned to lie between said ledges, said escutcheon plate 115 having its end edges folded around the end edges of the front member of the buckle body to interlock therewith, the body front and the escutcheon forming inner and outer panel-supporting and retaining means engaging the back and front faces of the interposed panel.

2. In a belt buckle, the combination with a buckle body embracing a front member formed with opposite slightly raised side 125 ledges extending from end to end of the buckle, an escutcheon member dimensioned to lie between said ledges and having its ends infolded around the respective end edges of the body front member to interlock the parts 130

together, one of said members having its interior portion formed with a shallow recess, a panel of ornamental material seated in said recess and confined therein by the engagement of said members with its front and back faces respectively.

3. A belt buckle body whose front is formed with raised side ledges and whose interior portion is depressed to form a shallow panel-receiving recess, a panel of ornamental material seated in said recess, an outer escutcheon plate having its interior portion cut out to expose said panel partly to view, said escutcheon plate being dimensioned to lie between the aforesaid side ledges and having its end edges interlocked with the end edges of the body front.

4. In a belt buckle, the combination with a buckle body front formed with raised side ledges, an escutcheon plate dimensioned to lie between said side ledges and having end flanges covering and detachably interlocking with the end edges of the body front, the interior portion of said escutcheon plate being cut out in any desired form, and a removable panel of ornamental material interposed and confined between the body front and the escutcheon plate to form an ornamental replaceable backing behind the cut out portions of the escutcheon plate. 20 25 30

In witness whereof, I have subscribed the above specification.

FRANK P. DAUGHADAY.
